WILLIAM M. JEWELL, OF CHICAGO, ILLINOIS, ASSIGNOR TO CHLORIDE PROCESS COMPANY, OF CHICAGO, ILLINOIS, A CORPORATION OF ILLINOIS.

ELECTROLYTIC CELL AND METHOD OF MAINTAINING THE EFFICIENCY THEREOF.

1,056,181.

Specification of Letters Patent. Patented Mar. 18, 1913.

Application filed December 17, 1912. Serial No. 737,164.

To all whom it may concern:

Be it known that I, WILLIAM M. JEWELL, a citizen of the United States, residing at Chicago, in the county of Cook and State of Illinois, have invented certain new and useful Improvements in Electrolytic Cells and Methods of Maintaining the Efficiency Thereof, of which the following is a specification, reference being had to the accompanying drawings.

My invention relates to electrolytic cells of the horizontal type, and more particularly to that type in which the electrolyte is separated, so to speak, into different strata by reason of the different density thereof, at different levels, or in different zones. Many attempts have heretofore been made to produce an electrolytic cell of this type which would maintain a high degree of efficiency, but so far as I am aware, they have not been successful, except to a limited extent. In a cell of this character I have found that it is highly important to maintain the anode liquor at a high degree of density, while the cathode liquor should be comparatively light as in that way the efficiency of the cell is increased, but heretofore in the practical operation of gravity cells where the anode and cathode liquors are, in a sense, separated by the difference in their specific gravities, and not by the use of a diaphragm, as the operation of the cell continues, the anode liquor becomes spent and the cathode liquor gradually becomes heavier, owing to its taking into solution some of the products of the decomposition of the electrolyte, so that in a comparatively short time the cathode liquor being the heavier sinks to the bottom of the cell. I have discovered that the obstacles heretofore encountered due to a heavier cathode liquor may be overcome and the efficiency of the cell be constantly maintained at a satisfactory point by placing the anode in the lower portion of the cell and the cathode in a relatively higher position, and maintaining the cathode liquor at all times at a lower state of density than the anode liquor, so that a stratification of the electrolyte that is the reverse of the usual horizontal cell stratification is preserved while the cell is in operation. The desired difference in density is secured by adding to the cathode liquor a suitable liquid, such as water, which will act to lighten the cathode liquor sufficiently to preserve the desired stratification.

This liquid may be added either constantly, or from time to time, during the operation of the cell as may be necessary to maintain the cell at its highest efficiency. I also provide means between the anode and cathode for collecting and removing the gases liberated at the anode. My invention is particularly advantageous in connection with cells, the purpose of which is to generate chlorin, or other gases, by decomposition of the electrolyte.

My improved cell, as illustrated in the drawings and as hereinafter described, provides for maintaining the maximum strength of the anode liquor notwithstanding its decomposition, and for conducting away the liquid, as well as the gaseous products of the electrolytic action.

In the accompanying drawings in which I have illustrated two forms of cells embodying my invention,—Figure 1 is a longitudinal vertical section on line 1—1 of Fig. 2; Fig. 2 is a horizontal section on line 2—2 of Fig. 1, the principal parts of the cell being, however, shown in plan view; Fig. 3 is a cross-section on line 3—3 of Fig. 2, the salt replenishing tank being partly broken away; Fig. 4 is a partial vertical section illustrating a modification; Fig. 5 is a partial plan view of the construction shown in Fig. 4; and Fig. 6 is a vertical cross-section on line 6—6 of Fig. 4.

Referring to the drawings,—7 indicates a tank or receptacle of suitable shape and dimensions, which is made of soap stone, or other suitable material. The cell shown in Figs. 1 to 3 is composed of two similar units, but it will be noted that the cell may comprise one or more units as desired. In the construction shown in said figures, the receptacle 7 is divided transversely near the center by two partitions 8—9 set a short distance apart, forming an intermediate chamber 10, into which the chlorin, or other gas liberated at the anodes, is conducted, and from which the anode liquor is replenished, as hereinafter described. The chamber 10 is inclosed by a cover-plate 11, which overlies the partitions 8—9 and the sides of the receptacle 7, as shown in Fig. 2. Near its ends 12—13, the receptacle 7 is also provided with transverse partitions 14—15, set a short distance from their respective ends of the receptacle, and between said partitions and the adjacent ends is a horizontal

partition 16, forming upper and lower chambers 17-18, at the ends of the receptacle, as shown in Fig. 1. The chambers 17 receive the effluent of the cathode liquor and the chambers 18 receive the effluent of the anode liquor, as hereinafter described. 19-20 indicate the compartments between the partitions 8-14 and 9-15, respectively, as illustrated in Fig. 2.

21 indicates the anodes, which are preferably of Acheson graphite, and which are arranged longitudinally in the lower portions of the compartments 19-20 and extend through the partitions 8-9 into the collecting chamber 10. In the illustration, said anodes are shown as formed from cylindrical rods of graphite which are cut down, except at their inner ends, into the form of slabs, the rounded inner ends of said anodes being preferably screw-threaded, so that they may be connected by bus bars 22, located in the collecting chamber 10, and rising through the cover 11 thereof, so that they may be conveniently connected to positive terminals 23, as shown in Fig. 1. The anodes 21 are placed near the bottom of the receptacle 7, resting at their ends upon suitable supports, such as cross-bars 24-25, located at the ends of the compartments 19-20, as shown in Figs. 2 and 3. These cross-bars may be of any suitable inert material.

26 indicates inverted troughs, which extend from end to end of the compartments 19-20, over the anodes therein, their ends resting on the supports 24-25. Said troughs are to confine the gases liberated at the anode and direct them to the collecting chamber 10, with which they communicate, through openings 27, which are located near the upper portions of said troughs, as best shown in Fig. 3.

28 indicates additional openings between the collecting chamber 10 and the space beneath the troughs 26, which may be termed the anode chambers, said openings serving to admit the replenished solution to said chambers, as hereinafter described.

29 indicates the cathodes, which are usually made of iron, and in the construction illustrated are in the form of comparatively thin L-shaped bars. They are arranged in the compartments 19-20, extending from end to end thereof at a higher level than the anodes, as shown in Fig. 3. As therein shown, the cathodes rest at their ends on supporting blocks 30, which rest on the cross-bars 24-25, but they may be supported in any other suitable way.

31 indicates bolts which connect the several cathodes together, so that the several cathodes of each unit may be connected to a common negative terminal 32, as shown in Fig. 1.

33 indicates passages in the partitions

14-15 which connect the anode chambers to the compartments 18, said passages being arranged at about the upper level of the anode liquor in said anode chambers. The purpose of said openings is to permit the spent brine to flow from the anode chambers into the compartments 18.

34 indicates pipes which lead from the compartments 18 to the inlet pipe 35 of a pump 36, which may be driven in any suitable way. 37 indicates a pipe leading from the outlet of said pump to the lower portion of a tank 38, adapted to contain salt, or equivalent material, for restoring the strength of the electrolyte. The upper portion of the tank 38 is connected by a pipe 40 with the upper portion of the collecting chamber 10, as shown in Fig. 2, so that the anode liquor passing into the compartments 18 may be circulated by the pump 36, through the tank 38, and back to the collecting chamber 10, from which it may again pass into the anode chambers, through the passages 28. The tank 38 is provided near one end with a transverse partition 39, which rises to the level at which it is desired to maintain the liquid in the tank 38, such level being somewhat higher than the outlet 40, so that the head of brine maintained in the tank 38 by the partition 39, determines the flow of brine through the pipe 40 into the collecting chamber 10. An overflow chamber 39^a is provided at the opposite side of the partition 39, which chamber communicates by a pipe 41 with the inlet pipe 35 of the pump, so that any brine overflowing the partition 39 flows back to the pump, through the pipe 41.

42 indicates a pipe leading from the upper portion of the compartment 39, which is closed by a cover 43, to the collecting chamber 10, for conducting any chlorin gas therein to said collecting chamber.

44 indicates an opening in the cover 43, through which air may be admitted to the tank 38, and 45 indicates an overflow outlet at the upper portion of the compartment 39^a.

46 indicates pipes for supplying water, or other liquid, to the compartments 19-20, outside of the trough 26, for diluting the cathode liquor.

47 indicates a funnel through which brine is supplied to the collecting chamber, for distribution to the several anode chambers, and 48 indicates a pipe for supplying brine to said funnel, as shown in Fig. 1.

49 indicates a chlorin outlet pipe which communicates with the upper portion of the collecting chamber 10, as shown in Fig. 1, for conducting away the chlorin generated.

The operation of the cell shown in Figs. 1, 2 and 3 when used to generate chlorin from a brine electrolyte is as follows: The cell is supplied with brine, a suitable liquid, such as water, being supplied to the upper part

tion of the cell, so that the liquor surrounding the anodes is heavier than that surrounding the cathodes, the proper difference in density being maintained by the admission of the lightening liquid either continuously or from time to time, as may be required. During the passage of the current through the cell chlorin is liberated at the anodes and sodium hydrate is formed at the cathodes, the chlorin being conducted by the troughs 26, to the collecting chamber 10, whence it passes out through pipe 49. The spent anode liquor is discharged through the outlet 33, to the compartment 18, whence it may pass through pipes 34 to the pump 36 and is then forced through pipe 37 to the compartment 38, where it takes up a fresh supply of salt and then passes back into the collecting chamber 10, and through it back to the anode chambers, through passages 28. The desired level of the cathode liquor is maintained in the cell by overflow into the compartment 17, through slots 50, in the partitions 14—15, as best shown in Figs. 1 and 2, whence it may be conducted away through outlets 51.

The provision of means for introducing fresh brine into the circulating electrolyte, as described, is an important factor in the efficiency of the cell, since the brine so supplied to the circulating anode liquor passes to a certain extent under the edges of the troughs and up to the cathode liquor. By this means the anode liquor of the cell is entirely changed in a certain period of operation, such period depending upon the volume of the brine feed and the anode contents of the cell. Thus the accumulation in the anode liquor of chlorates, or other objectionable products of the electrolytic action, is prevented. In a cell of the type shown in Figs. 1, 2 and 3 of the drawings, using 500 amperes of current, the brine feed may run from 75 c. c. to 150 c. c. per minute, and in such a cell the anode liquor contents would thus be displaced and renewed in less than each twenty-four hours of operation.

It will be noted that as best shown in Fig. 3, the anodes are at a lower level than the cathodes, so that by maintaining the difference in density, as described, the proper stratification of the electrolyte may be at all times maintained, with the result that the cell may be maintained constantly at a high degree of efficiency, regardless of the length of time during which it is in operation. The feed of water, or other liquid, to the cathode liquor is approximately the same in quantity as that of the brine feed above referred to. Where the cell is used with an electrolyte the decomposition of which does not tend to make the cathode liquor heavier, so that the operation of the cell does not disturb the stratification, it is not usually necessary to add a lightening liquid to the cathode liquor.

In Figs. 4, 5 and 6, I have shown a different form of cell in which the same results may be secured by maintaining the necessary stratification of the electrolyte as hereinbefore described. In the modified construction I employ a cell 52, which is preferably rectangular in form, and is separated by transverse partitions 53 into a series of transversely -arranged compartments. The upper portion of the cell is further divided transversely by a series of partitions 54, which extend from the upper portion of the cell downward, but terminate a short distance from the bottom of the cell, as shown in Fig. 4, thus providing a series of anode chambers 55, alternating with a series of cathode chambers 56. The anode chambers are closed at the top by cover-plates 57. 58 indicates a series of electrodes, preferably rods of graphite, or other suitable material, which extend through the several partitions 53 and the ends of the cell, as shown in Fig. 1, but present a greater surface to the cathode chambers than to the anode chambers. These rods may be paraffined or otherwise treated to prevent the passage of the electrolyte through them by capillary attraction. By connecting the end electrodes with the poles of a battery, or other suitable source of current, the several rods 95 become anodes and cathodes arranged respectively in the anode and cathode chambers. In this construction the requisite stratification is maintained by supplying water, or other lightening liquid, to the 100 cathode chambers, through pipes 59. The chlorin generated in the anode chambers escapes through pipes 60, communicating with the upper portions of said chambers, and connecting with a header 61, as shown in Fig. 5. The sodium hydrate formed in the cathode compartments escapes through pipes 62, to troughs 63, through which it may be conducted away. Brine is supplied to the anode chambers and caused to circulate 105 by pipes 64, which communicate with the several anode chambers at about the upper level of the anode liquor, and with an inlet header 65, provided with a funnel 66, or other suitable means for supplying fresh 115 brine thereto. The brine passes out of the anode chambers through pipes 67, said pipes communicating with a header 68. The several partitions 53—54 may be made of any suitable dielectric material and are preferably soapstone and glass, respectively. It will be understood that the same means for circulating and regenerating the anode liquor as shown in Figs. 2 and 3, may be used in connection with this construction also. 120 In this connection I wish to say that while in my improved construction the use of a diaphragm for the purpose of maintaining the separation of the anode and cathode liquors is usually unnecessary, my invention 130

does not exclude the use of a diaphragm, as one may be used if desired where it is advantageous. Furthermore, while I have described the cathode liquor as being above the anode liquor, it should be understood that my invention does not require the placing of the cathode liquor directly over the entire body of the anode liquor, but includes any suitable arrangement of the anode and cathode liquors in which the cathode liquor is carried by the anode liquor and the stratification of the electrolyte is maintained by the difference in the density of the cathode and anode portions thereof, the cathode portion being the lighter.

That which I claim as my invention, and desire to secure by Letters Patent, is,—

1. In an electrolytic cell of the horizontal type containing anode liquor and a lighter cathode liquor above the anode liquor, an anode in the anode liquor, a cathode in the cathode liquor, and means between the anode and the cathode for collecting and removing the gases liberated at the anode.

2. In an electrolytic cell of the horizontal type containing anode liquor and a lighter cathode liquor carried by the anode liquor, an anode in the anode liquor, a cathode in the cathode liquor, and means between the anode and the cathode for removing the gases liberated at the anode.

3. In an electrolytic cell of the horizontal type containing an electrolyte composed of anode and cathode liquors stratified by the difference in their specific gravities, the cathode liquor being the lighter, an anode in the anode liquor, a cathode in the cathode liquor, and means between the anode and the cathode for removing the gases liberated at the anode.

4. In an electrolytic cell containing an electrolyte composed of a heavier anode liquor in the lower portion of the cell, and a lighter cathode liquor in the upper portion thereof, an anode in the anode liquor, a cathode in the cathode liquor, and means between the anode and the cathode for col-

lecting and removing the gases liberated at the anode.

5. In an electrolytic cell containing an electrolyte composed of a heavier anode liquor in the lower portion of the cell, and a lighter cathode liquor in the upper portion thereof, an anode in the anode liquor, a cathode in the cathode liquor, and a gas conduit arranged between the anode and the cathode for collecting and removing the gases liberated at the anode.

6. The method of maintaining the efficiency of an electrolytic cell of the horizontal type which consists in preserving stratification of the electrolyte by maintaining the cathode liquor at a lower specific gravity than that of the anode liquor.

7. The method of maintaining the efficiency of an electrolytic cell of the horizontal type which consists in preserving stratification of the anode and cathode liquors by supplying a suitable liquid to the cathode liquor to keep its specific gravity lower than that of the anode liquor.

8. The method of maintaining the efficiency of an electrolytic cell of the horizontal type having anode and cathode liquors, an anode in the anode liquor and a cathode in the cathode liquor, which consists in supplying a suitable liquid to the cathode liquor as required to maintain it at a lower specific gravity than the anode liquor.

9. The method of maintaining the efficiency of an electrolytic cell of the horizontal type having an anode liquor and a lighter cathode liquor separated from the anode liquor by the difference in their specific gravities, an anode in the anode liquor and a cathode in the cathode liquor, which consists in supplying a suitable liquid to the cathode liquor as required to maintain it at a lower specific gravity than the anode liquor.
